UNITED STATES PATENT OFFICE.

HAROLD W. WISHART, OF HOLLYWOOD, CALIFORNIA, AND WILLIAM WISHART, OF CLINTON, IOWA, ASSIGNEES TO CLIMAX ENGINEERING CO., A CORPORATION OF DELAWARE.

ROTARY-COMPRESSOR REFRIGERATING MACHINE.

Application filed January 23, 1925. Serial No. 4,148.

This invention relates to a refrigerating unit incorporating a rotary compressor for the refrigerant.

It is an object of this invention to provide a unit type of refrigerating machine of simple and compact arrangement adapted for automatic control and incorporating an improved rotary compressor for the refrigerant. The present invention deals more particularly with the compression and cooling stages of the refrigerating cycle, the expansion stage taking place either adjacent a brine tank or in the refrigerator proper, both of which details have been omitted in this case because no novelty is involved therein.

It is an important object of this invention to provide an improved rotary compressor of the gyratory or pendulum type such as is shown in H. W. Wishart's pending application Ser. No. 533,736, filed February 2, 1922.

It is another object of this invention to provide an improved and highly efficient oil trap for separating oil from the compressed refrigerant.

It is a further object of this invention to provide a rotary compressor of the type described partly submerged in a bath of cooling, sealing, and lubricating fluid wherein the discharge from the compressor passes through an automatic valve and is conducted above the level of the cooling agent to avoid unnecessary admixture therewith, together with an otherwise unavoidable partial condensation of the refrigerant.

It is also an object of this invention to provide an improved housing for a pendulum type rotary compressor, having internal and external fins adapted to facilitate the maximum heat transfer from the refrigerant and the cooling liquid to the casing and thence to the atmosphere. Efficient cooling of the compressor reduces the required capacity thereof and therefore reduces the power demands as compared to a cycle involving adiabatic compression.

It is a further object of this invention to provide an improved piston enclosure and swivel block mounting wherein the enclo-

sure is adjustable to compensate for wear of the swivel block, which wear would otherwise result in serious leakage of the refrigerant.

It is another object of this invention to provide a vane secured to the oscillating piston with an improved gas seal at the joining line of the two pieces.

It is still another object of this invention to provide an improved cylinder and piston mounting in a rotary pump of the class described, wherein the rotating eccentric shaft is mounted on roller bearings permitting free relative axial movement of the piston and cylinder to prevent end grinding between the piston and cylinder walls; together with a thrust washer adapted to maintain the eccentric shaft in the proper position respective to the cylinder.

It is a further object of this invention to provide a rotary compressor operating in a bath of lubricant wherein the compressor shaft is drilled to convey oil to the friction surfaces under centrifugal force created by the rotation of the shaft.

It is also an object of this invention to provide an improved and self contained rotary compressor incorporated in a refrigerating unit of the least possible complication consistent with satisfactory service to the user.

Other and further important objects of this invention will be apparent from the specification and the accompanying drawings.

The invention (in a preferred form) is illustrated in the drawings and hereinafter more fully described.

On the drawings:

Figure 1 is a side elevation of a refrigerator unit embodying the features of this invention.

Figure 2 is an elevation of the compressor end of the unit.

Figure 3 is an enlarged vertical axial section of the rotary compressor taken on the line 3-3 of Figure 2.

Figure 4 is a vertical transverse section of the compressor taken on the line 4-4 of Figure 3.

Figure 5 is a section of a slightly modified form of piston and cylinder corresponding in part with Figure 4.

Figure 6 is a section of the suction passages to the compressor taken on the line 6-6 of Figure 3.

Figure 7 is an enlarged longitudinal section of the oil trap taken on the line 7-7 of Figure 2.

Figure 8 is a section on the line 8-8 of Figure 7.

Figure 9 is a section of the check valve used to prevent back flow from the high pressure side upon stopping the compressor, the section being taken on the line 9-9 of Figure 2.

As shown on the drawings:

The refrigerating unit comprises as a whole a rotary compressor, to be hereinafter described in detail, which is mounted as a unit on a base 10 and driven by a prime mover 11 connected to a fan and flywheel 12 of the compressor. The compressed refrigerant leaving the compressor is delivered in 25 to the bottom of a long horizontal tube 13 forming an oil trap arranged to drain back into the compressor casing through the delivery pipe 14 from the compressor. The entering refrigerant flows along the length 30 of this tube and the gaseous refrigerant finds an outlet through the inclined tube 15, the mouth of which is arranged at the highest point in the tube 13. This outlet 15 leads through the wall of the tube 13 and is connected to a valve manifold 16 and then by the connection 17 to a bank of double-walled cooling and condensing coils 18 through which a water circulation is maintained. The water supply and high and low side 35 refrigerant controls all center in the valve manifold 16 which is described in Patent No. 1,397,912 of November 22, 1921. A water switch 19 as connected to the water circulating system is indicated for the purpose of automatically shutting down the compressor upon failure of the water supply. The condensing coils 18 discharge the liquid refrigerant into a storage tank or bottle 20 mounted along said base 10, which also 40 serves as a support for all the apparatus mentioned herein. The liquid refrigerant is drawn from the storage bottle as needed in the refrigerator compartment expansion and evaporating coils which are connected to 45 the valved outlet 21. The return lead from the expansion coils enters a scale trap 22 thence to the valve manifold and through a check valve 23 and strainer 24 leading to the inlet passage 25 formed by the boss 26 50 on the casing 53. This passage aligns with an inlet port 27 on the cylinder wall of the compressor proper.

Axially positioned within the casing 53 is a drive shaft 28, the projecting end of 55 which carries the flywheel 12. This shaft

is provided with an eccentric section 29 on either side of which are mounted counterweights 30. Mounted on the eccentric 29 is a roller bearing 31 supporting a piston 32. The use of a roller bearing permits free 70 axial adjustment of the piston relative to the shaft to prevent end thrust by the piston which would involve large power losses as well as rapid wear thereof. Mounted on the shaft on either side of the counterweights are 75 other roller bearings 33 the outer races of which are secured in cylinder side walls 34 and 35, the side wall 34 being hereinafter referred to as the suction plate and the other as the discharge plate. An enclosing cylinder 80 36 is clamped between the two plates and the assembly bolted to the wall of the casing 53. A cylindrical rocker sealing member 37 which may be made in two segments as shown in Figure 5, is positioned in 85 a suitable aperture formed in a depending boss 38 on the bottom of the cylinder and this rocker is apertured to receive a reciprocating partition or blade 39, the inlet or suction port 27 opening into the cylinder 90 space 40 on one side of this blade and a similar discharge port on the other side of this blade leads to the enclosed discharge valve 41 from which the compressed refrigerant 95 is led above the surface of the lubricant and sealing liquid by the pipe 42.

The rocker sealing member and the aperture therefor require careful fitting to maintain a fluid seal and to maintain this seal the cylinder boss 38 may be split as shown 100 in Figure 5 to allow subsequent adjustment to the closest working clearance permissible. The partition blade is riveted in suitable recesses in the piston and to maintain a fluid seal at the joint a hole is reamed half in 105 each part and a sealing pin 43 is driven therein to form a gas stop.

The casing 53 is provided with external cooling fins 44, air being blown thereover by fan blades formed in the flywheel 12. 110 Fins 45 are also formed on the inside surface of the casing to improve the heat transfer from the cooling and lubricating fluid therein, which is maintained at a level above the axis of the shaft (28). The shaft is 115 drilled as at 46 from the outboard end to provide an oil lead, radial outlets 47 being provided on either side of the eccentric to lubricate the roller bearings, these radial outlets having a centrifugal pumping action 120 due to the rotation of the shaft, thus rendering the compressor self-lubricating as long as the oil level is maintained at the proper height. The outboard end of the shaft also carries a thrust collar 48 and 125 washer 49 bearing against the discharge plate 35 thus maintaining the proper position of the eccentric with respect to the cylinder.

The casing 53 is closed by a cover 50 130

which carries a sight gauge 51 with pointers 52 indicating the permissible high and low oil levels within the casing.

The operation is as follows:

- 5 Rotation of the crankshaft 28 and eccentric actuates the piston which has a continuous rolling contact with the cylinder ring. During this rolling motion the partition blade has an oscillating in and out reciprocating motion in the rocker. The whole movement of the piston may be likened to an inverted pendulum. The refrigerant enters through the inlet 25 and suction plate 34, the rotation of the piston serving to 10 gradually draw the blade out of the rocker as the point of contact of the piston and cylinder advances forming a crescent-shaped space to receive the refrigerant. As the point of rolling contact advances the suction space increases to a maximum when the point of contact travels around to the blade position, whereupon the gas is trapped in this space and compressed by continued rotation of the point of contact, a suction cycle 15 proceeding at the same time the previous charge is being compressed and delivered through the discharge valve into the space in the casing above the sealing oil, from which the gas flows to the oil trap and 20 thence to the condenser coils and storage bottle.

We are aware that numerous details of construction may be varied through a wide range without departing from the principles 35 of this invention and we therefore do not purpose limiting the patent granted hereon, otherwise than necessitated by the prior art.

We claim as our invention:

1. In a compressor of the class described, 40 a cylinder, a shaft journalled therein, an eccentric on said shaft, a piston on said eccentric, a rocker adjustably mounted in the cylinder to maintain sealing engagement therein, and a blade secured to said piston and slidably engaged in said rocker.

2. In a compressor of the class described, 45 a cylinder, a shaft, an eccentric on said shaft within the cylinder, a piston on said eccentric, a rocker adjustably mounted in said cylinder, a blade fixed relatively to the piston and slidably in said rocker, and a plug driven between said blade and said piston adapted to form a gas seal therebetween.

- 50 3. In a device of the class described a casing having internal and external cooling fins, a rotary compressor mounted within said casing, and a bath of lubricant partly submerging said compressor, and an oil trap adapted to receive the discharge from the compressor comprising a receiver and a gas collecting tube leading from a high point in the receiver, said receiver being adapted to drain back into said casing.

- 55 4. In a device of the class described a cas-

ing having internal and external cooling fins, a rotary compressor mounted within said casing, a bath of lubricant partly submerging said compressor and a discharge valve for said compressor having an outlet 70 extending above the level of the lubricant within said casing, and an oil trap adapted to receive the discharge from the compressor comprising a receiver and a gas collecting tube leading from a high point in the receiver, said receiver being adapted to drain back into said casing.

5. In a rotary compressor, a fixed cylinder, a rotating shaft journalled therein, an eccentric on said shaft, a piston on said eccentric, counterweights on said shaft opposed to said eccentric, a partition blade secured to said piston and a rocker for said blade adjustably mounted in said cylinder. 80

6. In a rotary compressor, a driving shaft 85 having an eccentric thereon and an axial passage and radial outlets from said passage adjacent the points requiring lubrication, a piston mounted on said eccentric, a cylinder surrounding said piston and having bearings on the eccentric shaft on either side of the eccentric, a rocker mounted in said cylinder, a partition blade secured to the piston and reciprocating in said rocker, and a gas seal between said blade and piston 90 comprising a plug driven between the mating surfaces thereof.

7. In a rotary compressor, a driving shaft having an eccentric thereon and an axial 100 passage and radial outlets from said passage adjacent the points requiring lubrication, a piston mounted on said eccentric, a cylinder surrounding said piston and having bearings on the eccentric shaft on either side of the eccentric, a rocker mounted in an 105 adjustable boss in said cylinder, and a partition blade secured to the piston and reciprocating in said rocker.

8. In a rotary compressor, a driving shaft 110 having an eccentric thereon and an axial passage and radial outlets from said passage adjacent the points requiring lubrication, a roller bearing on said eccentric, a piston mounted thereon, a cylinder surrounding said piston, roller bearings for the cylinder 115 mounted on the shaft on either side of said eccentric, a rocker mounted in an adjustable boss in said cylinder, and a partition blade secured to said piston and reciprocating in said rocker.

9. An oil trap adapted to receive the discharge from a compressor comprising a horizontal tube having a bottom inlet at one end for the discharge from the compressor, and an inclined collecting tube extending 125 within the horizontal tube and having its opening adjacent the top of the horizontal tube at the end opposite the inlet.

10. In a rotary compressor, a shaft, an eccentric thereon, a cylinder axially dis-

- posed relative to the shaft, end walls for the cylinder having journals for said shaft, a piston mounted on said eccentric, a blade secured to said piston, and a rocker for said blade adjustably mounted in said cylinder to maintain sealing engagement therein.
11. A rotary compressor comprising a casing, a cylinder therein, a rocker in the cylinder, means for adjusting the cylinder to fit the rocker, a piston in said cylinder, a blade on said piston slidably engaged in said rocker, and eccentric means for operating said piston to cause the compression of a fluid by the compressor.
12. A rotary compressor comprising a casing, a cylinder therein, a rocker in the cylinder, means for adjusting the cylinder to fit the rocker, a piston in said cylinder, a blade on said piston slidably engaged in said rocker, a rigid gas stop inserted between the mating surfaces of the blade and the piston and eccentric means for operating said piston to cause the compression of a fluid by the compressor.
13. A rotary compressor comprising a casing, a cylinder therein, a rocker in the cylinder, means for adjusting the cylinder to fit the rocker, a piston in said cylinder, a blade on said piston slidably engaged in said rocker, a shaft having an eccentric adapted to actuate said piston, a roller bearing between the eccentric and the piston and roller bearings supporting the shaft in the cylinder.
14. A rotary compressor comprising a casing, a cylinder therein, a rocker in the cylinder, means for adjusting the cylinder to fit the rocker, a piston in said cylinder, a blade on said piston slidably engaged in said rocker, a shaft having an eccentric
- adapted to actuate said piston, a roller bearing between the eccentric and the piston, roller bearings supporting the shaft in the cylinder, said shaft being drilled to provide centrifugal oil pumping for lubricating the bearings.
15. A rotary compressor comprising a casting, a cylinder therein, a rocker in the cylinder, means for adjusting the cylinder to fit the rocker, a piston in said cylinder, a blade on said piston slidably engaged in said rocker, a shaft having an eccentric adapted to actuate said piston, a roller bearing between the eccentric and the piston, roller bearings supporting the shaft in the cylinder and a thrust bearing on said shaft adapted to locate the same relative to the cylinder.
16. In a rotary compressor a cylinder, a shaft mounted axially of the cylinder, an eccentric on said shaft, a piston mounted on the shaft eccentric within the cylinder, counterweights secured to said shaft to balance the eccentric and piston, and oil passages formed in said shaft adapted to centrifugally oil the rotating parts.
17. A compressor comprising an internally finned casing having a lubricant therein, a cylinder in said casing partially submerged in the lubricant, a drive shaft projecting into the casing and into said cylinder, said drive shaft having an axial passage with radial outlets within the cylinder adapted to form a lubricant pump, an eccentric associated with said shaft, and a piston in said cylinder supported on said eccentric.

In testimony whereof we have hereunto subscribed our names.

HAROLD W. WISHART.
WILLIAM WISHART.
